(57) **CLAIM**

The ornamental design for a clasp for strap or belt, as shown and described.

DESCRIPTION

FIG. 1 is a perspective view of the clasp for strap or belt in an open position.

FIG. 2 shows a top plan view of the clasp for strap or belt in the open position, showing environmental structure.

FIG. 3 shows a top plan view of the clasp for strap or belt in a closed position.

FIG. 4 shows a sectional view of the clasp for strap or belt along line 4-4, as indicated in FIG. 3.

FIG. 5 shows a perspective view of the clasp for strap or belt in an alternative configuration; and,

FIG. 6 shows a perspective view of the clasp for strap or belt in the closed position.

The portions of the clasp for strap or belt shown in broken lines forms no part of the claimed design. The broken lines in FIG. 2 illustrate environmental structure and form no part of the claimed design. The dot-dot-dash broken lines define the bounds of the claimed design and form no part thereof.
